UNITED STATES PATENT OFFICE.

WILLIAM S. MARSHALL, OF CHICAGO, ILLINOIS, ASSIGNOR OF ONE-HALF
TO HENRY H. McGAFFEY, OF INDIANAPOLIS, INDIANA.

PUMP.

SPECIFICATION forming part of Letters Patent No. 289,288, dated November 27, 1883.

Application filed March 15, 1883. (No model.)

To all whom it may concern:

Be it known that I, WILLIAM S. MARSHALL, of the city of Chicago, county of Cook, and State of Illinois, have invented certain new and useful Improvements in Pumps, of which the following is a specification.

The nature and object of my said invention will be fully disclosed by the following detailed description.

- 10 Referring to the accompanying drawings, which are made a part hereof, and on which similar letters of reference indicate similar parts, Figure 1 is a side elevation of a pump embodying my said invention; Fig. 2, a central vertical section of the same; Fig. 3, a section of the working parts similar to a portion of Fig. 2, but on an enlarged scale; Fig. 4, a horizontal sectional view, looking downwardly from the dotted line $z z$; Fig. 5, a view as seen when looking downwardly from the dotted line $y y$; Fig. 6, a top or plan view of the removable portion of the base only, on a still further enlarged scale; Fig. 7, a central vertical section thereof on the dotted line $x x$,
25 the base-plate with which it engages being shown in dotted lines; Fig. 8, a top or plan view of so much of the base-plate G as shows the hole therein and the notches in its edge; and Fig. 9, a view of the clamp which holds
30 the air-chamber and parts immediately adjacent thereto, similar to a portion of Fig. 2, but on the scale of Figs. 6, 7, and 8.

In said drawings, the portions marked A B represent the large and small portions, respectively, of the cylinder; C, the induction-pipe; D, the eduction or discharge pipe, which is also the valve-rod; E, the air-chamber, which also forms the support for the handle and one of the supports for the cylinder; F, a vacuum-chamber, which also forms another support for the cylinder; G, a base for the pump, which rests upon the platform; H, said platform, and I the connecting-rod by which the pump is driven. The cylinder A B is the usual two-size cylinder ordinarily used in this class of pumps. It has the lifting-valve a and the forcing-valve b , which are connected together by the rod b' . It also has the ordinary check-valve a' . There is a free
45 passage from the inside of the cylinder part B to the combined valve-rod and discharge-

pipe D, through which the water is regularly forced by the usual and ordinary operation of the pump. The pipe C is simply an ordinary induction-pipe. The pipe D has attached thereto at the lower end the valve b , and through the rod b' the valve a . The air-chamber E is a tube connected to a projecting portion, a^2 , on the cylinder A. It extends up through the plate G to a suitable height to support the handle, 60 and has a bracket, E', upon its top, upon which the handle is mounted. Said bracket also forms a cap for the air-chamber, and extends out and forms a guide, i , for the rod I. This air-chamber is secured to the plate G by 65 clamps g g' , as shown most plainly in Fig. 5. As shown in Figs. 2 and 9, one part, g , of this clamp is formed in one piece with the base-plate G, and the other, g' , is loose and secured to the first by bolts, as shown in Figs. 1 and 70 5. By loosening these bolts the tube E may be moved up or down to any desired point and there secured by tightening said bolts. This provides for any adjustment that may be required.

The combined vacuum-chamber and cylinder-support F is secured to the cylinder A in much the same manner as is the combined air-chamber and support E, and to the base-plate G by being screwed into a suitable cap or boss 80 formed thereon. It communicates with the base of the cylinder A below the check-valve a' , and is constructed perfectly air-tight. The effect is to aid in making the flow of water in the pipe C continuous during the operation of 85 pumping. The plate G is placed upon the platform, and practically forms that part thereof of which immediately surrounds the pump. In order that the working parts may be removed for repair, &c., without disturbing the 90 whole pump, the central portion, G', of this plate is made removable. Said portion is of sufficient size that when removed a hole will be left, through which the cylinder portion B and the valves a and b may be withdrawn and 95 replaced. In order that this may be conveniently done, the portion G' and the edges of the hole which it is intended to cover are constructed to interlock. Notches g^3 in said edge are adapted to receive projections g^4 on the 100 portion G'. The portion G', after the projections g^4 have been inserted in the notches g^3 , is

turned partly around, and thus, by the aid of said projections and the overlapping edges g^1 , interlocks with the plate G in a firm and secure manner, as indicated by the dotted lines in Fig. 5. 5 The under side of the plate G, with which the projections g^1 come in contact, may be inclined, in order that there may be a wedging action as the portion G' is turned, and the devices thus drawn closely together. The platform H can be 10 any ordinary curbing or platform which is usually employed to cover a well. The connecting-rod I is mounted in bearings i^1 i^2 , and serves to connect the valve-rod either to the handle I' or to a pitman from a windmill or similar power. 15 It is attached to the combined valve-rod and discharge-pipe D by a swivel-joint, d, and thus said pipe is permitted to turn in any direction without affecting the connecting-rod. The handle I' is an ordinary pump-handle. It is 20 mounted upon a link, c', which is pivoted to the bracket E', and is connected by a pivot, i, to the rod I.

It will be seen by an examination of the drawings that several of the parts of my improved 25 pump each serve two or more purposes, which are usually only accomplished by the use of separate devices. It can be quickly and easily put in position and as easily taken apart for purposes of readjustment or repair.

Having thus fully described my said invention, what I claim as new, and desire to secure 30 by Letters Patent, is—

1. The combination, in a pump, of the two-

size cylinder A, B, the combined valve-rod and discharge-pipe D, the connecting-rod I, and 35 means of operating the same, said combined valve-rod and discharge-pipe being connected to said connecting-rod by the swivel-joint d, substantially as set forth.

2. The combination of the cylinder, the combined valve-rod and discharge-pipe D, the connecting-rod I, connected to said pipe D by a 40 swivel-joint, and the handle or pitman for driving the same, substantially as set forth.

3. The combination of the cylinder, the combined valve-rod and discharge-pipe, the connecting-rod I, connected to said rod by a swivel-joint and mounted in slides to insure a vertical movement, and the handle I', connected to said rod and mounted on a link, e', said link 50 being mounted on a pivot-bearing, substantially as set forth.

4. The combination, with a pump, of a base, G, having a removable portion, G', and a clamp, g', one part of which is formed in one piece 55 with said base, and the other part is formed independently of the base, substantially as set forth.

In witness whereof I have hereunto set my hand and seal, at Indianapolis, Indiana, this 60 12th day of March, A. D. 1883.

WILLIAM S. MARSHALL. [L. S.]

In presence of—

C. BRADFORD,
E. W. BRADFORD.
